UNITED STATES PATENT OFFICE.

CHESTER A. RICH, OF CINCINNATI, OHIO, ASSIGNOR TO THE RICH PUMP COMPANY,
OF CINCINNATI, OHIO, A CORPORATION OF OHIO.

LADDER.

1,353,270.

Specification of Letters Patent. Patented Sept. 21, 1920.

Application filed March 21, 1919. Serial No. 284,088.

To all whom it may concern:

Be it known that I, CHESTER A. RICH, a citizen of the United States of America, and a resident of Cincinnati, in the county 5 of Hamilton and State of Ohio, have invented a new and useful Improvement in Ladders, of which the following is a specification.

One of the principal difficulties encountered in ladders as ordinarily constructed is the loosening of the rounds in the course of time, thus rendering the ladder somewhat unsafe and also affording loose joints wherein water may accumulate and eventually 15 cause the rounds to rot within the sides or rails of the ladder.

An object of my invention is to produce an improved ladder in which loosing of the rounds through shrinkage and other causes 20 is prevented throughout the lifetime of the ladder.

This and other objects are attained in the ladder described in the following specification and illustrated in the accompanying 25 drawing, in which:—

Figure 1, is a perspective view showing the portions of the ladder in position ready for the assembling operations, the sides or rails being shown fragmentally.

30 Fig. 2, is a fragmental perspective view of the ladder after assembling the elements thereof.

Fig. 3, is a fragmental front elevation of the ladder upon an enlarged scale.

35 Fig. 4, is a side elevation of the portion of the ladder disclosed in Fig. 3, and also upon an enlarged scale.

Fig. 5, is a much enlarged view of an end 40 of a ladder round in position within the socket provided for it in the side or rail of the ladder.

My improved ladder consists of the usual side rail members 7 and 8, and the usual rounds 9 which form the steps of the ladder.

45 As is common in all ladder constructions the

ends 10 of each round are somewhat reduced and fit within the openings 11 provided at spaced intervals in the sides. To prevent separation of the sides from the rounds I preferably drive brads or other fastening 50 devices 12 through the sides and through the ends 10 as shown in Figs. 2, 3 and 4.

Thus far the description of my improved ladder applies also to ordinary ladders. The feature of novelty of my ladders consists in the treatment of the elements of the ladder preparatory to the assembling operation. I prepare the ends 10 of each round by thoroughly creosoting them so that the wood is thoroughly impregnated. After 60 this operation the elements are assembled in the manner above described. The action of the creosote upon the ends 10 is to prevent the wood thereof from shrinking within the sockets 11, provided in the rails 7 and 8, 65 thus avoiding the gradual loosening of the ladder elements with relation to each other and simultaneously preventing to a great extent the forming of pockets or recesses for the entrance of moisture which would result 70 in rotting either the ends 10 or the wood of the sockets 11 in the sides of rails 7 and 8 of the ladder.

Having thus described my invention that which I claim is:—

1. A ladder comprising rails and rounds 75 located between the rails, the ends of the rounds having an impregnation of material adapted to prevent shrinkage thereof within the rails.

2. A ladder comprising rails having 80 sockets therein, and rounds having their ends creosoted, and located within the sockets, whereby shrinkage of the ends within the sockets is prevented.

In testimony whereof, I have hereunto 85 subscribed my name this 19th day of March, 1919.

CHESTER A. RICH.
